EDWIN FERGERSON STEWART, OF NEW YORK, N. Y.

DUPLEX STRAINER.

1,288,257.

Specification of Letters Patent. Patented Dec. 17, 1918.

Application filed August 8, 1917. Serial No. 186,084.

To all whom it may concern:

Be it known that I, EDWIN F. STEWART, a citizen of the United States, residing at New York, in the county of New York and State of New York, have invented certain new and useful Improvements in Duplex Strainers, of which the following is a specification.

My invention relates to devices for straining liquids, such as coal tar or other fluids, and concerns particularly an improved construction of such devices whereby I am enabled to readily and thoroughly clean the strainer chambers without resorting to tools such as wrenches, etc., for getting at the contents of the strainer chambers.

In the types of construction of duplex strainers hitherto in use, as a result of the necessity of keeping such strainers liquid tight against the comparatively heavy water pressures maintained in such strainers, it has been deemed necessary to so position the covers for the strainer and other chambers making up the duplex strainer that the use of tools is required in order to clean the device when not in use or to clean the particular strainer chamber which is not being used. By my invention I am enabled to obtain an improved form of construction possessing among many advantages subsequently to be enumerated the desirable advantage of being readily assembled and disassembled without the use of any tools whatsoever. Referring to the drawing wherein I have illustrated one embodiment of my invention,

Figure 1 shows in vertical section along line C—C of Fig. 4 the duplex strainer of my invention;

Fig. 2 is a vertical section of the same along line A—A of Fig. 1;

Fig. 3 is a vertical section of the same along line B—B of Fig. 1;

Fig. 4 is a plan view of the device with the lever operating member for the valve and member closing central chamber omitted; and

Fig. 5 is a cross-section of the device along the line D, D of Fig. 1.

Referring to the various figures of the drawing, the device consists essentially of a chambered casting 1 which is in cross-section of substantially oval shape and is divided by the partition walls D, D' into the central valve chamber B and the side strainer chambers A, C. The partition walls are integral

with the inner walls of the sides of the chambered casting 1, and are intermediate the ends of such casting so as to leave the clear spaces 2, 3 above and below the partition walls respectively. The lower end of the chambered casting 1 is provided with the integral wall 4 which has a flange 5 and a central reduced aperture 6 corresponding and collinear with the central valve chamber B. At the top of the chamber B are the ports F, F' and at the bottom the ports G, G', these ports serving as communications between the central valve chamber B and the side strainer chambers A, C.

The upper open end of the chambered casting 1 is provided with the three removable cover members H, J, and H' covering the upper open ends of the chambers A, B and C respectively, while the lower aperture 6 is provided with the removable cover member J'.

Each of the strainer chambers A, C is provided with the substantially circular internal flanges N, N' adjacent the upper end of the said chambers and of the partition walls D, D'. Mounted on said flanges N, N' are the foraminous flanged receptacles R, R' which may be constructed of any type and size of screening material adapted to serve as strainer means. Eye bolts S, S' are provided in the flanges 7, 7' of the strainer receptacles R, R' to serve the double purpose of providing means whereby the strainer receptacles may be readily removed from the strainer chambers for cleaning and also as a means to securely position the strainer receptacles upon the flanges N, N'. This latter result is accomplished by means of providing the cover members H, H' with the inner flanges 8, 8' which bear upon the tops of the eye bolts S, S' when the covers are in place and serve in this way to securely position the strainer receptacles upon the flanges N, N'.

The cover plates H, H' are machined so that a tight joint is effected between the bearing surfaces of such cover plates H, H' and the top flanges of the chambers A, C, which top flanges are also machined to a true surface to receive suitable gaskets 9, 9' upon which the cover plates are forced down by the means illustrated. This means comprises the screws L, L' mounted in the swinging yokes K, K' which are in turn mounted on the two pairs of studs M, M and M', M' cast as an integral part on the ex-

terior walls of the chambers A and C. The covers H, H' are further provided with eye bolts P, P' which serve as handles to facilitate the removal of such covers. The screws 5 L, L' are provided with the hand wheels Q, Q' of sufficient size to permit forcing the cover firmly into its seat so that no leakage whatever will occur, without the use of levers or other tools. The valve chamber B 10 is of substantially rectangular cross-section taken along a horizontal plane, throughout its central part corresponding with the vertical length of the partition walls D, D'. The portions above and below the central 15 part of the valve chamber are circular in cross-section in a horizontal plane, the circular portions above and below being provided with the inlet ports F, F' at the upper end of the chamber B and the outlet ports G, G' 20 at the lower end of said chamber, these ports as already described opening into the opposite ends of the chambers A and C.

Chamber B is further divided into two 25 parts by the partition wall E, the upper part of which is provided with the inlet opening I, while the lower part below the partition wall is provided with the outlet opening O. Valve members in the form of substantially circular segments are provided as shown at T, T' to close the ports F and G and F' and G', as the case may be, these valves moving in the angular 30 grooves U and U' formed between the rings V, V' and the flanged covers J, J'. The 35 rotating valves T, T' are connected by the lever castings X, X' which are loosely mounted on a shaft 10 of substantially square cross-section extending along the axis of chamber B and engaging studs Y, Y' cast as integral parts of the valves T, T'. The central shaft is pivoted at the center of the inner face of the cover member J', passes through the double bushing 9" centrally mounted in the partition member E, extends through a suitable stuffing 45 box in the cover member J, and is provided at its upper end with the lever Z as a means for rotating the shaft and moving the valves T, T' so that they may cover 50 the upper and lower ports F, G or F', G', as the case may be, and thereby cut off means of communication between the central valve chamber B and either one of the side strainer chambers A or C respectively.

55 In operation the lever Z of the valve member is swung around so that it is substantially centrally over the axis of that particular strainer chamber which is to be left in operation, as where the same has been 60 previously cleaned, the lever, therefore, providing an indicator to show that the valves T, T' cover the ports leading to the opposite chamber which is the one to be cleaned, and that communication between 65 the central valve chamber and the strainer

chamber to be cleaned is cut off, while communication between the central valve chamber and the side strainer chamber to be left in operation is open. The liquid to be strained enters by the inlet I and, as shown 70 in the adjustment of the device illustrated in Fig. 1, passes upward and through the open port F' into the chamber C downward and outward through the strainer R', through the bottom port G' and thence upward and out through the outlet O. In such passage the solid material which it is desired to remove from the liquid is left in the strainer basket from which it may readily be removed during a subsequent 75 cleaning operation. When the strainer member R' has been in operation for a sufficiently long time, the valve lever Z is turned so that the same is over the axis of the chamber A which has meanwhile been 80 properly cleaned, thereby putting the chamber C out of operation and putting the clean chamber A into operation. To effect a cleaning of the chamber C all that it is necessary to do is to turn the hand wheel 85 Q' releasing the pressure exerted by the screw L' upon the cover member H', whereupon the swinging yoke K' carrying the screw L' and the hand wheel Q' is rotated to expose the cover member H' to permit 90 the same to be removed from its seat on the chamber C by means of the handle member P'. The removal of the cover H' releases the pressure exerted on the eye bolts S' by the flange 8' of the cover H', thereby 95 permitting the strainer receptacle R' to be removed and cleaned and giving ready access to the chamber C for cleaning or other purposes.

The advantages of this type of construction are obvious from the above description. Without interrupting the continuity of the straining operation and without resorting to the use of tools, a construction is provided that permits of ready assemblage 105 and effective and easy cleaning of the device.

While the invention has been illustrated in connection with two strainer chambers, it would be understood that more than two 110 may be used without departing from the spirit of the invention.

What I claim is:

1. A duplex strainer comprising a hollow member; a fixed diaphragm dividing said member into upper and lower portions; an inlet for liquid communicating with one of said portions; an outlet for said liquid communicating with the other of said portions; two strainer chambers connected to 120 said member and each provided with ports communicating with both of said portions; strainer means within each of said chambers; segmental valves for closing the ports between either of the said chambers and the 125 130

said portions while leaving open the ports between the other of the said chambers and the said portions; and a single valve stem for controlling said valves.

- 5 2. A strainer comprising an elongated hollow member; a fixed diaphragm dividing said member transversely into two portions; an inlet for liquid communicating with one of said portions; an outlet for 10 said liquid communicating with the other of said portions; elongated strainer chambers associated with said hollow member, each chamber being provided with a port at each end of the same adjacent the said member and communicating with the said hollow portions; strainer means in each of said strainer chambers; segmental valves for closing the ports between any one of the said chambers and the said portions while 15 leaving open the ports between the other of the said chambers and the said portions; and a single valve stem for controlling said valves.

3. A duplex strainer comprising a substantially closed hollow body; two partition walls within the hollow body dividing the same into a central valve chamber and two side strainer chambers; a transverse diaphragm within and affixed to the central 25 valve chamber dividing said valve chamber into an inlet and an outlet chamber; an inlet for liquid communicating with said inlet chamber; an outlet for said liquid communicating with said outlet chamber; removable strainer means positioned within each of said strainer chambers, each of said strainer chambers being provided with a port at each end thereof adjacent the said valve chamber and communicating with said 30 inlet and outlet chambers; and valve controlled means within the valve chamber for closing the ports between either of the said strainer chambers and the said inlet and outlet chambers while leaving open the 35 ports between the other of said strainer chambers and the said inlet and outlet chambers.

4. A duplex strainer comprising a hollow, substantially cylindrical body entirely open 50 at one end and having a reduced central opening at the other end; two partition walls within and spaced from the ends of the hollow body and dividing the same into a central valve chamber and two side strainer 55 chambers; a transverse diaphragm within and affixed to the central valve chamber dividing said chamber into an inlet and an outlet chamber; an inlet for liquid communicating with said inlet chamber; an outlet 60 for said liquid communicating with said outlet chamber; removable strainer means positioned within each of said strainer chambers; each of said strainer chambers being provided with a port at each end 65 thereof adjacent the said valve chamber

and communicating with said inlet and outlet chambers; removable covers for the reduced opening and for the open ends of the valve and strainer chambers, the covers for the strainer chambers serving also to position the strainer means; hand operable means for positioning the covers over the open ends of the strainer chambers in a liquid tight manner; and valve controlled means within the valve chamber, said valve 70 controlled means comprising a valve spindle rotatably supported in the diaphragm and the covers for the valve chamber and the reduced opening, and valves associated with the said spindle at each end thereof for 75 closing the ports between either of the said strainer chambers and the said inlet and outlet chambers while leaving open the ports between the other of said strainer chambers and the said inlet and outlet chambers. 80

5. A duplex strainer comprising a closed hollow body; two partition walls within the hollow body and dividing the same into a central valve chamber and two side strainer chambers; a transverse diaphragm within 90 and affixed to the central valve chamber dividing such valve chamber into an inlet and an outlet chamber; an inlet for liquid communicating with said inlet chamber; an outlet for said liquid communicating with 95 said outlet chamber; removable strainer means positioned within each of said strainer chambers; each of said strainer chambers being closed at one end and open at the other end, and having a side wall of the same provided with inlet and outlet ports adjacent the ends of the valve chamber, an interior flange spaced from but located near the open end of the strainer chamber, a foraminous strainer receptacle supported within 100 said strainer chamber upon said flange, elongated means associated with said strainer receptacle serving as means to assist in the removal of the same, a removable cover for the open end of the strainer chamber, said cover serving to position the strainer receptacle in place on the said flange, hand operable means adjacent the said open end and associated with the strainer chamber for applying great pressure to said cover to position the same on the said open end in a liquid tight manner; and valve controlled means within the valve chamber for closing the ports between either 105 of the said strainer chambers and the said inlet and outlet chambers while leaving open the ports between the other of said strainer chambers and the said inlet and outlet chambers. 110

6. A duplex strainer comprising a hollow, 125 substantially cylindrical body entirely open at one end and having a reduced central opening at the other end; two partition walls within and spaced from the ends of the hollow body and dividing the same into 130

a central valve chamber and two side strainer chambers; a transverse diaphragm within and affixed to the central chamber dividing said chamber into an inlet and an outlet chamber; an inlet for liquid communicating with said inlet chamber; an outlet for said liquid communicating with said outlet chamber; removable strainer means positioned within each of said strainer chambers; each of said strainer chambers being closed at one end and open at the other end, and having a side wall of the same provided with inlet and outlet ports adjacent the ends of the valve chamber; an interior flange spaced from but located near the open end of the strainer chamber, a foraminous strainer receptacle supported within said strainer chamber upon said flange, elongated means associated with said strainer receptacle serving as means to assist in the removal of the same, a removable cover for the open end of the strainer chamber, said cover serving to position the strainer receptacle in place on the said flange, hand operable means adjacent the said open end and associated with the said strainer chamber for applying great pressure to said cover to position the same on the said open end in a liquid tight manner; removable covers for the reduced opening and for the open end of the valve chamber; a valve controlled means within the valve chamber for closing the ports between either of the said strainer chambers and the said inlet and outlet chambers while leaving open the ports between the other of said strainer chambers and the inlet and outlet chambers.

5 10 15 20 25

7. In a liquid strainer a central chamber and side chambers; outlet and inlet ports leading from the said central to the said side chambers; a fixed diaphragm dividing the central chamber into two portions; a valve stem extending through said diaphragm; said valve stem having valves controlling said ports so as to close one outlet and the corresponding inlet port while leaving the other ports open.

In testimony whereof I affix my signature.

EDWIN FERGERSON STEWART.
